UNITED STATES PATENT OFFICE.

WILLIAM A. SCHLEICHER, OF CLEVELAND, OHIO.

DESIGN FOR A TOE-RAIL FOR VEHICLES.

SPECIFICATION forming part of Design No. 22,771, dated September 5, 1893.

Application filed June 5, 1893. Serial No. 476,876. Term of patent 14 years.

To all whom it may concern:

Be it known that I, WILLIAM A. SCHLEICHER, of Cleveland, in the county of Cuyahoga and State of Ohio, have invented a new and original Design for Patterns for Toe-Rails for Vehicles, of which the following is a full, clear, and exact description, reference being had to the accompanying drawing, which shows in plan view the surface of a toe-rail for vehicles, having the pattern which constitutes my design.

My design consists in a pattern for the surface of a toe-rail, said pattern comprising a series of distinct quadrilateral figures composed of projecting beads, said figures being arranged in series with opposite angular corners directed lengthwise of the series, substantially as shown in the accompanying drawing, and hereinafter described.

In the drawing, 2 represents the toe-rail, 20 which is of ordinary shape. On the surface of the rail, is the pattern consisting of a series of distinct quadrilateral figures 3, the sides of which are composed of projecting beads, as shown. These several figures 3 have 25 opposite corners directed lengthwise of the series and respectively opposite to each other. 4, 4, are other beads arranged on the toe-rail.

I claim—

The design for a pattern for toe-rails substantially as herein described and shown.

In testimony whereof I have hereunto set my hand.

WILLIAM A. SCHLEICHER.
